UNITED STATES PATENT OFFICE.

JOSIAH DOW, OF LOWELL, MASSACHUSETTS.

DUPLEX-CRANK PISTON-PUMP.

SPECIFICATION forming part of Letters Patent No. 318,968, dated June 2, 1885.

Application filed March 10, 1884. (No model.)

To all whom it may concern:

Be it known that I, JOSIAH Dow, a citizen of the United States, residing at Lowell, in the county of Middlesex and State of Massachusetts, have invented certain new and useful Improvements in Duplex-Crank Piston-Pumps; and I do hereby declare that the same is fully described in the following specification, and illustrated in the accompanying drawings.

This invention relates to improvements in duplex-crank piston-pumps, particularly well adapted for pumping liquids, and in this capacity to be used either as a suction or force pump, although the invention is equally well adapted for use as an air-pump or blower for force or exhaust purposes, as well as a water-motor, if so desired.

The invention is carried out as follows, reference being had to the accompanying drawings, where Figure 1 represents a side elevation of my improved pump. Fig. 2 represents an end view thereof, as seen from X in Fig. 1. Fig. 3 represents a central longitudinal section on the line A B, shown in Fig. 2. Fig. 4 represents a cross-section on the line C D, shown in Fig. 3. Fig. 5 represents a cross-section on the line E F, also shown in Fig. 3; and Fig. 6 represents a top view of the cylindrical valves. Fig. 7 represents a side view of one of the piston-cylinders; and Fig. 8 represents a cross-section on line G H, shown in Fig. 7.

Similar letters refer to similar parts whenever they occur on the different parts of the drawings.

a' is the shell, cast in one piece, the portion a constituting the pump-cylinder, and the portion a' is the cylindrical valve-chamber.

a" is the base, cast in one piece with the aforesaid shell, it being a continuation of the cylindrical valve-chamber a' in case the latter is arranged below the pump-cylinder a, as shown in the drawings; but I do not wish to confine myself to this precise arrangement, as the valve-chamber a' may be located above or on one side of the pump-cylinder a, if so desired, although I prefer to arrange and locate the respective valve and pump cylinders in the manner as shown.

Within the shell a' is cast a division-wall, a", extending from the top of the pump-cylinder

der a to the bottom of the valve-cylinder a', in a plane parallel to the ends of said shell, as shown in Fig. 3, such division-wall having a cylindrical cut-away portion, a', concentric with the pump-cylinder a, as shown in said Fig. 3, to permit a communication between the hollow cylinders of the duplex pistons, as will hereinafter be more fully described.

b and c represent the heads, secured air and water tight to the open ends of the shell a a' by means of suitable bolts and nuts or screws, as shown in the drawings. The head c is provided with an opening, c', leading to the central part of pump-cylinder a, and is in open communication with the suction-pipe d, the upper flange of which is secured air and water tight to the outer end of head c by means of suitable bolts and nuts or screws, as shown in Fig. 3.

e is the pump-shaft, located in one end in a bearing, b', cast in one piece with the head b, and provided there with a packing-gland, b", made in the shape of an annular ring, or in two semicircular halves, as may be desired, said gland being kept in its proper place in said bearing by means of a suitable cap, b', and cap-screws, as is usual on pillow-blocks or shaft-bearings.

b' is a suitable packing at the inner end of gland b", as shown in Fig. 3, so as to make a perfectly tight joint between the shaft e and that part of the head b where it projects through.

In its other end the shaft e is supported in a bearing, d', cast in one piece on the outside of suction-pipe d, and provided there with a gland, d", cap d', and packing d', in a similar manner as described relative to the bearing b'. I wish to state, however, that I do not confine myself to any particular bearings for said shaft e, as I may, if so desired, use the ordinary stuffing-boxes, such as used on piston-rods of steam-engines without departing from the essence of my invention.

The shaft e is set in a rotary motion in its bearings by means of belt or other power applied to a suitable pulley secured to said shaft, or in any other well-known manner.

To the shaft e is secured firmly the hollow cylinder f, by means of its central hub, f', and screw-shaped suction or guiding wings f" f". (Shown in Fig. 4.) The object of said

screw-shaped wings $f'' f''$ is to aid in creating a vacuum in the interior of said cylinder f when it is rotated, and thus facilitate the liquid passing out through the side opening f^3 (on 5 the periphery of cylinder f) and into the pump-cylinder a . I prefer to make the outer end of the guiding-wings f'' with a propeller-shaped edge, f^{10} , to facilitate the passage of fluids to the interior of the pump from supply-10 pipe, as represented in Figs. 7 and 8.

In one piece with cylinder f is cast the piston f^4 , which is located in front of opening f^3 , and extending outward and sidewise sufficiently to fill the space between the exterior 15 of cylinder f and interior of pump-cylinder a , as shown in Fig. 4.

$f^5 f^6$ are side webs, connecting the piston f^4 with the cylinder f , so as to impart the necessary strength to the piston.

20 By means of the screw-shaped wings $f'' f''$ the cylinder f is divided into two compartments, f^6 and f^7 , the former communicating with the side opening, f^3 , and the latter passing entirely through from end to end of said 25 cylinder, so as to establish a communication from the suction-pipe d to the second cylinder g , secured to shaft e behind the first-named cylinder, f .

f^8 is a packing made of metal or wood, and 30 placed in a groove on the sides and end of piston f^4 , so as to effect a tight joint between the said piston and the plane and curved parts of cylinder a .

$f^9 f^{10}$ are segmental packing-rings, located in 35 corresponding recesses on the outer side edges of cylinder f , so as to effect a tight joint between the ends of cylinder f and corresponding interior walls of pump-cylinder a . These packing-rings may be made of wood or metal.

40 On the shaft e , in a line with the cylinder f , is secured the secondary cylinder g , having central hub, g' , screw-shaped guide-wings $g'' g''$, side opening, g^3 , piston g^4 , piston-webs $g^5 g^5$, compartment g^6 , packing g^8 , and segmental 45 packing-rings $g^9 g^{10}$, like those described forming part of cylinder f . The cylinders f and g are so secured to each other and to their common shaft e as to cause their pistons f^4 and g^4 to project outward in diametrically-opposite 50 site directions, and so that the compartment f^7 in cylinder f stands in direct communication with the compartment g^6 in cylinder g , as shown in Fig. 3.

i is the valve-cylinder shaft, which shaft is 55 located in bearings $i' i'$, cast in one piece respectively with the heads b and c , and provided with glands i'' , caps i^3 , and packings i^4 in a similar manner as the bearings for the pump-shaft e .

60 The shafts e and i are geared together by the respective gears k and l , the former secured to shaft e and the latter to shaft i , both of said gears being of equal size and having equal number of teeth, as shown in Figs. 2 and 3, 65 so that the shaft i shall be turned around its axis exactly one revolution for every revolution of shaft e .

Below the cylinder f is secured on shaft i the valve-cylinder m , the outside diameter of which is made equal to that of the cylinder f , and as said cylinders are rotated in opposite directions they are made to bear against each other—that is, just to touch each other without causing any frictional resistance, as shown in Figs. 3, 4, and 5. m' is the central hub of valve-cylinder m , and $m'' m''$ are the skeleton arms uniting the said hub with the valve-cylinder m , so as to make it as light as possible consistent with the strength necessary. 75

m^3 is a cut-away portion on one side of the valve-cylinder m , to permit the piston f^4 to enter it and to pass by the valve-cylinder m when said piston in its rotation approaches the said valve-cylinder, as illustrated by position in Fig. 5. The concave curvature of the cut-away portion m^3 is to be made such as to make a close joint between it and the outer end of the piston f^4 during the rotation of said piston and valve-cylinder, and thus to prevent waste of liquid when the piston is passing by 90 the valve-cylinder.

$m^4 m^4$ are webs at the sides of the cut-away portion m^3 , as shown in Figs. 3 and 4, the space between such webs being equal to the width of the piston f^4 , so as to enable the latter to 95 enter between them when it passes into the concavity m^3 , and thus more effectually to prevent leakage while the piston f^4 is in the act of passing by the valve-cylinder m .

$a^5 a^5$ are lateral grooves on the interior of valve-chamber a' , in which are located suitable metal or wood packings, $m^5 m^5$, held up by means of springs, or in other equivalent manner, against the outside of the valve-cylinder m , as shown in Fig. 4, such packings being 105 located near the junction of the respective pump and valve chambers a and a' , as shown, so as to effect a close connection between the exterior of valve-cylinder m and its chamber at such places.

$m^6 m^6$ are segmental packing-rings, located in corresponding grooves at the ends of the valve-cylinder m , so as to effect a close joint between the ends of the latter and the corresponding parts of its chamber. 115

Within the valve-chamber a' , I prefer to make a semicircular (or nearly so) cut-away part or segmental space, a^6 , to permit the valve-cylinder m to move with greater ease and with the least frictional resistance. 120

n is the valve-cylinder, secured to shaft i directly below the cylinder g . Said valve-cylinder n is made in all respects like the valve-cylinder m , and like it has central hub, n' , skeleton arms $n'' n''$, concave cut-away portion n^3 , webs $n^4 n^4$, and packings $n^5 n^5$, $n^6 n^6$, the only difference between said valve-cylinders being in their arrangement upon the shaft i , for as the pistons $f^4 g^4$ are arranged on the shaft e in diametrically-opposite directions, so are the cut-away portions $m^3 n^3$ of the valve-cylinders $m n$ arranged correspondingly in diametrically-opposite directions, as shown. The cylinders $f g$ and their respective pistons 130

$f^4 g^4$ are made to counterbalance each other on the shaft e , and in a like manner the valve-cylinders $m n$ are arranged upon the shaft i so as to counterbalance each other accurately, 5 and thus to prevent any pounding or jarring of the pump while in motion.

a^7 is the delivery-opening from the pump-chamber a , which opening communicates with the air-chamber a^8 , cast in one piece with the 10 shell $a a'$, and having an exit, a^9 , through which the water is delivered from the pump in a continuous stream. If the liquid from the pump is to be conducted at any distance from it, I attach a suitable pipe to the exit a^9 15 in any ordinary manner, according to circumstances.

In using this my improved pump the liquid or air may be drawn in through pipe d and delivered through opening a^9 , or vice-versa, 20 according to the direction in which the shaft e is rotated.

The operation of this my improved duplex-crank piston-pump is as follows: We will suppose that the pump is to be used for drawing water up through suction-pipe d , and to force it out through exit-opening a^9 . For this purpose the shaft e , its cylinders $f g$, and pistons $f^4 g^4$ are set in a rotary direction. Shown by arrow in Fig. 4.) The shaft i and its 25 valve-cylinders $m n$ are by means of gears $k l$ accurately coupled to shaft e , and made to rotate with equal velocity in an opposite direction, as shown by arrow in said Fig. 4. After a few rotations the interior of the pump-chamber a is filled with the liquid which is 30 being drawn up through pipe d , and after passing through opening c' in the head c it enters the compartments f^6 and f^7 in the pump-cylinder f on both sides of the screw-shaped wings f'' , causing a portion of the liquid to be forced 35 out through opening f^8 , back of piston f^4 , into the pump-chamber, and the other part of the liquid conducted through channel g^8 and forced out through opening g^9 , back of piston g^4 , into 40 the other half of the pump-chamber on the other side of the division-wall a^3 , the water in front of the respective pistons $f^4 g^4$ being forced out through opening a^1 into air-chamber a^8 , and delivered through exit a^9 , as described. 45 During this operation the respective valve-cylinders m and n are kept in a continuous rotary motion in opposite direction to that of the pistons $f^4 g^4$, and of precisely equal speed with the latter, and in such a manner as to bring 50 the pistons $f^4 g^4$, respectively, in conjunction with the concavities $m^3 n^3$ on the respective valve-cylinders $m n$, and thus to permit said pistons in their revolutions to pass by the said valve-cylinders without causing leakage in so 55 doing.

I am aware of the existence of a rotary blower consisting of two or more revolving vanes having curved sides, revolving segments having concave recesses adapted to said 60 vanes, a chest-easing adapted to the vanes and segments, and a valve operating in unison with both the vanes and segments for con-

trolling the outlet of the blast. I am also aware of the existence of a rotary pump consisting, essentially, of one or more spiral inclined scoops or pistons and an eccentric drum rotating with the same and forming a bearing for the inner edge of an abutment-valve. Such devices are different from mine, since 70 they do not involve the use of a hollow cylinder open for supply at one end, and having internal suction-wings covering passages leading out to the periphery of said cylinder. 75

Having thus fully described the nature, construction, and operation of my invention, I 80 wish to secure by Letters Patent and claim—

1. In a pump, the rotary hollow cylinder f , provided with screw-shaped internal wings, f'' , and formed with an inlet-channel at its end, said channel on one side of said wings 85 extending through to the opposite end of the cylinder and on the other side through the periphery thereof, substantially as described.

2. In a pump, the hollow cylinder f , formed with a supply-channel having its inlet at the 90 end of said cylinder, a discharge-channel leading out through the periphery of the cylinder, and internal suction-wings located in said discharge-channel and forming a continuous guide for the fluid through said channel, substan- 95 tially as described.

3. In a pump, the shell, a , constituting a piston-chamber, in combination with an abutment-valve and a cylinder located within said shell and provided with a piston extending 100 from its periphery and formed with a supply-channel communicating with an opening through the shell, said opening surrounding the shaft upon which the cylinder rotates and covering the open end of said cylinder, the 105 supply-channel communicating with the piston-chamber through the periphery of its internal cylinder, the said piston-chamber having an exit-opening through the shell, substan- 110 tially as described.

4. In a pump, the rotary hollow cylinder f , with its internal guide-wings, $f'' f''$, side opening, f^8 , internal passage, f^6 , piston f^4 , piston-packing f^8 , and segmental packings $f^9 f^9$ at the outer edges of cylinder f , as set forth. 115

5. In a pump, the shell a , having recess a' , the valve-cylinder m , fitted within said recess and having the portion m^4 cut away, in combination with the cylinder f , provided with the piston extending from its periphery and 120 formed with an internal supply-channel communicating between the inlet-opening c' and the piston-chamber, the said inlet-opening surrounding the shaft upon which the cylinder rotates and covering the open end of said cylinder, said shell also having the exit-opening a^1 , and the shafts of the cylinder f , and valve-cylinder m geared together, substantially as 125 described.

6. In a pump, the shell $a a'$, with its perforated division-wall a^3 , the rotary shaft e , having attached to it the respective hollow cylinders $f g$, located side by side, in communication, and having diametrically-opposed open- 130

ings $f^3 g^3$ and pistons $f^4 g^4$, in combination with the shaft i , equally geared to shaft e by means of gears k and l , and having secured to it the respective valve-cylinders $m n$, each one having its cut-away portions $m^3 n^3$ arranged in diametrically-opposite positions and balancing each other, as set forth and described.

7. In a pump, the shell $a a'$, cast in one piece, the portion a adapted to serve as a pump-chamber for the reception of the rotary piston and intermediate connecting mechanism to the driving-shaft e , and having an air-chamber, a^8 , formed on the side thereof and communicating directly with discharge-opening a^1 , in combination with an abutment-valve arranged in the part a' , substantially as described.

8. In a pump, the shell $a a'$, having grooves $a^5 a^6$ for the reception of wood or metal packings $m^3 n^3$, combined with the valve-cylinders $m n$, secured in diametrically-opposite positions on shaft i , and having segmental packing-rings $m^6 n^6$ at the junction of sides and ends of the said respective valve-cylinders, substantially as set forth.

25 9. The combination of the shell a , the hollow cylinder f , having piston f^4 , extending from its periphery, the guide and suction wings $f'' f''$, forming an internal supply-passage hav-

ing its inlet at the end and its discharge at the periphery of said cylinder, the said inlet communicating with the opening c' through the shell, and the supply-pipe d , covering said opening, and the shaft e , passing through said opening c' and the supply-pipe d , substantially as described.

30 10. In a pump, the rotary hollow cylinder f , with its internal guide or suction wings, $f'' f''$, having outer propeller-shaped edges, $f^{10} f^{10}$, at entrance from supply-pipe d , as shown and described, to facilitate the passage of the fluid 40 to the interior of the pump, as set forth.

11. In a pump, the hollow cylinder f , having a piston extending from its periphery and provided with curved internal suction-wings forming continuous guides for the fluid in its 45 passage through an internal channel having its inlet at the end and its exit through the periphery of said cylinder, substantially as shown.

50 In testimony whereof I have affixed my signature in presence of two witnesses.

JOSIAH DOW.
